UNITED STATES PATENT OFFICE.

HENRY J. ECK, OF CHICAGO, ILLINOIS, ASSIGNOR TO ROBERTS & SCHAEFER COMPANY, OF CHICAGO, ILLINOIS, A CORPORATION OF ILLINOIS.

AUTOMATIC REVERSIBLE HOIST.

Application filed December 3, 1924. Serial No. 753,583.

To all whom it may concern:

Be it known that I, HENRY J. ECK, a citizen of the United States, residing at Chicago, in the county of Cook and State of Illinois, have invented a certain new and useful Improvement in an Automatic Reversible Hoist, of which the following is a specification.

My invention relates to a hoist, and particularly to a hoist adapted for use in coaling stations, although it may be used for other purposes. One object of my invention is to provide a particularly compact and efficient hoisting mechanism. Another object is to provide a hoisting drum in which the gearing or driving mechanism is enclosed within the drum. Another object is to provide a compact driving connection within an oil containing closure. Another object is to provide a hoisting drum which shall be self-locking, when the drive is discontinued. Other objects will appear from time to time in the course of the specification and claims.

I illustrate my invention more or less diagrammatically in the accompanying drawings wherein:

Figure 1 is a vertical, axial section;

Figure 2 is a section on the line 2-2 of Figure 1; and

Figure 3 is a section on the line 3-3 of Figure 1.

Like parts are illustrated by like symbols throughout the specification and drawings.

A is any suitable supporting surface on which are mounted the upwardly projecting piers A¹ upon which the hoist is mounted. BB are brackets supported on and permanently secured to the piers in any suitable manner.

C is any suitable motor means, herein shown as an electric motor. Its shaft C¹ is secured by means of the flexible coupling C² to the drive shaft D which is thereby rotated by the motor at the same rate of revolution as the motor.

EE¹ are supporting sleeves mounted in said brackets B and having at their inner ends the generally circular radial webs E² E³. E⁴ is a spacing and supporting element intermediate the webs E² E³ and spaced between them by the spacing sleeves E⁵. E⁶ are bolts passing through the webs E² E³ and the spacing member E⁴ and the spacing sleeves E⁵, and securing the entire assembly together. The shaft D rotates within the

bearings D⁴ D⁵ D⁶ mounted within the elements EE¹.

On the shaft D is a pinion F which meshes with three equal sized pinions F¹ each of which rotates about a pin F² supported in a radial projection F³ from the member E¹. These pinions mesh with the internally toothed ring gear G which is connected by the web G¹ to the hub G² which rotates about the shaft D. Keyed to or integral with the hub G² is the pinion G³ which is in mesh with three pinions H keyed to the three shafts H¹ which rotate in the bearings H² supported in the webs E² E³, and the spacing element E⁴ above mentioned. Each such shaft H¹ has mounted thereon an eccentric H⁶ which rotates within a corresponding aperture J in the large gear J¹. As the large spur gear J¹, by its eccentric motion revolves, it climbs around the inside of the internal ring gear K. The gear K is bolted, for example, by the bolts K¹ which pass through the flanges K², to the hoisting drum L.

The drum L rotates about the sleeves EE¹ and is supported thereupon by means of the webs LL¹ through which the bolts K¹ also pass. The webs LL¹ terminate on the bearing hubs L² L³ which are in bearing engagement with the bushings L⁴ L⁵ about the sleeves EE¹. L⁶ is an oil inlet provided with any suitable closure and L⁷ is an oil outlet, provided with any suitable closure it being understood that the webs LL¹ enclose the entire working mechanism in a substantially oil tight housing.

On one of said hubs L² is mounted a gear M in mesh with a pinion M¹ which controls a shaft M² which actuates the switch mechanism diagrammatically illustrated at M³, the details of which form no part of the present invention. The switch box M³ is mounted in any suitable manner on the bracket B.

It will be understood that, as the drum rotates, the cam shaft M² actuates a switch mechanism which is connected with the motor C and serves to stop the rotation of the motor after a predetermined rotation of the drum. After a predetermined interval of rest the switch releases the motor for a rotation of predetermined length in the opposite direction.

It will be understood that while I have illustrated an operative device, nevertheless many changes may be made in the size, num-

ber, shape and disposition of parts without departing from the spirit of my invention, and that I wish my description and drawings to be taken as in a broad sense illustrative rather than as limiting me to the specific mechanism described and shown.

The use and operation of my invention are as follows:

- I provide a hoist which is, in the first 10 place, self-locking. The eccentric gyrating gear J^1 travels about the gear K , as it is gyrated by the eccentric members controlled by the gears H , and gives to the gear K a positive rotation. The rotation of the shaft 15 D , in response to rotation of the motor, drives the ring gear K and the drum L through a double reduction, through the pinion F , the pinions F^1 , the ring gear G , the pinion G^1 , the pinions H , the eccentrics 20 H^1 , the gear J^1 and the internal ring gear K . When the motor is at rest the drum L cannot rotate, regardless what the tension on the hoist cable may be. Assuming that the motor is at rest and that the weight on the cable tends to rotate the gear K , as shown 25 in Figure 3, in counter-clockwise direction, the gear K , through its gear teeth, tends to pull the eccentric gear J^1 in the same direction. However this pull tends to rotate the eccentric gear about the uppermost shaft 30 H^1 in the same direction as the pull of the cable, thus tending to lift up the right side of the eccentric gear, as shown in Figure 3. This pull immediately locks the gear K , 35 since the eccentric gear J cannot be lifted, being held against such movement by the other eccentric shafts H^1 . In the operation of my hoist I therefore need use no separate brake, the driving connection between 40 drive shaft and drum automatically braking when rotation of the drive shaft ceases. In order to use my hoist for intermittent and regularly timed hoisting, for example in the operation of a coaling bucket or skip, I 45 provide any suitable automatic switch which stops the motor after a predetermined excursion of the hoist bucket in either direction, and which restarts the motor in opposite rotational direction after a predetermined 50 interval. In the form herein shown I actuate the switch in response to the gear M on the hub L^2 of the drum, the gear being in mesh with a gear M^1 on the switch controlling shaft M^2 . Thus after a predetermined 55 number of revolutions of the drum the switch breaks the circuit which actuates the motor, and any suitable means may be provided to actuate the switch, and to restart the motor after a predetermined pause.
- Setting up my hoist is a process of peculiar simplicity, since no bearings are to be aligned, all bearings being supported in or 60 on a single fixed supporting element comprising the members EE^1 which are bolted together in permanent relationship. Thus

the bearings are all trued up at the factory as the inevitable result of the correct assembling of correctly formed castings and correctly proportioned bearing bushings. The necessity of a meticulous alignment of 65 motor and hoist is to a great extent obviated by the use of a flexible driving connection.

I assemble my hoist with all the driving connection housed within the drum itself. My hoist therefore occupies a small floor 70 space, and requires small foundation. It is compact, and easy and safe to operate. There are no exposed gears and bearings and the entire driving connection may be kept in a bath of oil, the drum forming an oil- 75 tight housing.

I claim:

1. In a hoist, a drum, a fixed bearing sleeve about which said drum rotates, a drive shaft penetrating said bearing sleeve, 80 and means for rotating it, and a driving connection between said drive shaft and said drum, and comprising a gear on said drive shaft, a plurality of pinions in mesh therewith, a ring gear surrounding and in mesh 85 with said pinions, a gear of substantially smaller diameter than said ring gear connected thereto, a plurality of pinions in mesh therewith, eccentrics associated with each of said pinions, a gyrating gear having 90 rotary bearing relation with said eccentrics, an internal ring gear surrounding said gyrating gear and in mesh with it and of greater diameter than said gear, said ring 95 gear being connected to the drum. 100

2. In a hoist, a drum, a fixed bearing sleeve about which said drum rotates, a drive shaft penetrating said bearing sleeve, and means for rotating it, and a driving connection between said drive shaft and said 105 drum, and comprising a gear on said drive shaft, a plurality of pinions in mesh therewith, a ring gear surrounding and in mesh with said pinions, a gear of substantially smaller diameter than said ring gear connected thereto, a plurality of pinions in mesh therewith, eccentrics associated with each of said pinions, a gyrating gear having 110 rotary bearing relation with said eccentrics, an internal ring gear surrounding said gyrating gear and in mesh with it and of greater diameter than said gear, said ring 115 gear being connected to the drum, said driving connection being housed within said drum. 120

3. In a hoist, a drum, a fixed bearing sleeve about which said drum rotates, a drive shaft penetrating said bearing sleeve, and means for rotating it, and a driving connection between said drive shaft and said drum, comprising a gear on said drive shaft, an internal ring gear on said drum and a plurality of intermediate gears, a plurality of supporting webs for said intermediate gears outwardly 125 projecting from said bearing sleeve, an in- 130

termidiate spacing and supporting element, connecting means passing through said outwardly projecting webs and said intermediate spacing element, end members for said 5 drum rotatable about the outer surface of said fixed bearing sleeve, a drum rim member, and a plurality of transverse securing members passing therethrough and adapted to secure the drum rim and end members 10 together.

4. In a hoist, fixed bearing and supporting members, a composite bearing sleeve mounted therein, said sleeve comprising a pair of axially aligned apertured cylindrical 15 members, a drive shaft penetrating said members, a hollow drum rotatable about the cylindrical exterior of said members, a driving connection between said drive shaft and said drum, including a gear on said 20 drive shaft, an internal ring gear on said drum, and a plurality of intermediate gears, supporting and bearing webs for said gears, outwardly projecting from said bearing sleeve members, an intermediate spacing and 25 supporting element positioned between said webs, and transverse connecting members passing through said webs and said intermediate member and securing the bearing sleeve members together as a unit, said sup- 30 porting and bearing webs and driving con-

nection being entirely enclosed within the drum.

5. In a hoist, fixed bearing and supporting members, a composite bearing sleeve mounted therein, said sleeve comprising a 35 pair of axially aligned apertured cylindrical members, a drive shaft penetrating said members, a hollow drum rotatable about the cylindrical exterior of said members, a driving connection between said drive shaft and 40 said drum, including a gear on said drive shaft, an internal ring gear on said drum, a plurality of intermediate gears, supporting and bearing webs for said gears, outwardly projecting from said bearing sleeve 45 members, an intermediate spacing and supporting element positioned between said webs, transverse connecting members passing through said webs and said intermediate member and securing the bearing sleeve 50 members together as a unit, said supporting and bearing webs and driving connection being entirely enclosed within the drum, said drum forming a substantial oil tight 55 casing having oil inlet and outlet apertures and closing means therefor.

Signed at Chicago, county of Cook and State of Illinois, this 1st day of December 1924.

HENRY J. ECK.
